Primary Examiner—Raphael Barkai*Assistant Examiner*—Randall H Gholson(74) Attorney, Agent, or Firm—Lerner, David, Littenberg, Krumholz & Mentlik, LLP(57) CLAIM

The ornamental design for a fixed flat panel display mount, as shown and described.

DESCRIPTION

FIG. 1 is a front perspective view of our design for a fixed flat panel display mount;

FIG. 2 is a rear perspective view thereof;

FIG. 3 is a left side view thereof (the right side being a mirror image of the left side view);

FIG. 4 is a top plan view thereof; and,

FIG. 5 is a bottom plan view thereof.

The broken lines shown on the drawings are included for the purpose of illustration and form no part of the claimed design.
